[57] CLAIM

The ornamental design for a bottle, as shown and described.

DESCRIPTION

FIG. 1 is a perspective view of a bottle showing my new design with a spout attachment shown in broken lines for illustrative purposes only;

FIG. 2 is a side elevation thereof;

FIG. 3 is a top plan view thereof;

FIG. 4 is a side elevation as seen from the opposite side of FIG. 2;

FIG. 5 is a bottom plan view thereof;

FIGS. 6 and 7 are opposite end elevation views thereof; and

FIGS. 8, 9, 10, 11 and 12 are sectional views taken along respective lines depicted in FIG. 2.
